UNITED STATES PATENT OFFICE.

SAMUEL L. OTIS, OF AMSTERDAM, NEW YORK, ASSIGNOR OF ONE-HALF TO
JOHN H. GILES, OF SAME PLACE.

GARMENT-TURNING DEVICE.

SPECIFICATION forming part of Letters Patent No. 372,324, dated November 1, 1887.

Application filed August 2, 1887. Serial No. 245,945. (No model.)

To all whom it may concern:

Be it known that I, SAMUEL L. OTIS, of Amsterdam, in the county of Montgomery and State of New York, have invented certain new and useful Improvements in Garment-Turning Machines; and I do hereby declare the following to be a full, clear, and exact description of the invention, such as will enable others skilled in the art to which it appertains to make and to use the same.

My invention relates to an improved device for turning the sleeves and legs of garments in the process of manufacturing the same, and particularly knit underwear.

In the joining of knit garments that are not woven seamless it is necessary to reverse the sleeves of shirts or legs of drawers once, and in some cases twice, while they are being joined at the seams, and afterward to turn the seams inside, leaving the right side of the garment outside when it is finished. This turning of legs and arms of the under-garment has heretofore been done by the workman without aid of any implement by drawing the sleeves (or legs) over his arms until the extremities are reached. Then by grasping the free edge of the leg or sleeve and stripping the garment off of his arm the operator succeeds in turning the right side out. The reversal of underwear in the manner just indicated is tedious and consumes valuable time, as but one sleeve or leg can be operated upon at a time.

The object of my present invention is to produce a simple and comparatively inexpensive device that may be affixed to a work-table in such a position as to be convenient for instant use, and that by its employment will greatly facilitate the work as well as save time by affording a means of reversing both sleeves or legs of a shirt or pair of drawers at one operation.

With this object in view my invention consists in certain features of construction and combinations of parts, that will be hereinafter described, and pointed out in the claims.

In the drawings making a part of this specification, Figure 1 is a perspective view of the device, showing in dotted lines a garment thereon in the act of being turned. Fig. 2 is a side elevation of the garment-turning device.

C represents a low table such as is gener-

ally used by tailors or other operatives on garments, who use it for a seat as well as a means of support for their work. Upon the top and side boards, C C', of the table a bracket-plate, B, is secured by screws or other similar means. 55

The bracket-plate B is preferably made of metal. It is composed of two flanges, a a', of equal length, integral and at right angles to each other in cross-section, to adapt them to conform to the surface of the top and side of the table to which they are attached, as stated. On the vertical flange a' of the bracket-plate B two upright standards, A A, are adjustably fixed.

The standards A A are located between the 65 ribs or ledges 1 2 3 4, that are parallel projections with the edge of the plate a', the ledges serving to retain the standards from lateral displacement. Said standards A A have slots b cut through them, these slots extending from 70 near their lower ends upwardly a sufficient distance to receive set-screws c c, which are inserted in threaded holes made to receive them in the plate a'.

The bodies of the standards A A are tapered 75 edgewise to properly reduce them from a point just above the upper ends of the slots b to their upper extremities, and upon these upper ends the metal rings A' A' are affixed permanently.

The rings A' A' (see Fig. 2) project at right 80 angles outwardly on the side of the standards that will face the operator when he is about to use the device.

The relative height of and distance between the standards A A is such that they will be 85 convenient for use when a workman stands in front of them, and, further, that will enable the operator to place garments upon the rings, as will presently be explained. An adjustment of the standards on the plate a' by means 90 of the set-screws c affords a ready means for changing their height to suit the varying lengths of different-sized garments.

When the garment-turner is to be put in use, the garments, which have been previously 95 placed in accessible position on the table, are taken by the operator and placed, cuff end of the sleeve or lower end of the drawers, (as the case may be,) through the rings from above and drawn downward until the crotch or joined 100

portion reaches the rings, when the body of the garment is grasped and drawn downward over and on the outside of the rings, giving the legs or sleeves a reverse or upward movement, thus removing them from the rings, and thereby turning them inside out or right side out, as the case may be. This completes the operation, and the garment may be quickly removed from the device.

15. It is evident that the standards A A and their rings A' A' may be supported in other ways than that herein described and be used to accomplish the same purpose; hence I do not wish to limit myself to the employment of a table on which to support these standards and their rings. Other slight changes might also be made in the constructive features of my invention without violation of its spirit. I desire, therefore, to have such reasonable latitude in its manufacture as will lie fairly within its scope.

Having fully described my invention, what I claim as new, and desire to secure by Letters Patent, is—

25. 1. In a device for turning garments, two upright standards located a short distance apart, each standard having at its upper end a ring slot, the slot being located at or approximately at right angles to its standard, substantially as set forth.

30. 2. In a device for turning garments, the combination, with a bracket-plate, a supporting-base for the bracket-plate, and two vertical standards adjustably secured to the bracket-

plate, of two rings affixed to the upper ends of the standards and extending nearly horizontal from corresponding sides of the standards, substantially as set forth.

3. In a device for turning garments, the combination, with two upright standards and two rings affixed about at right angles on the top ends of these standards to extend upon corresponding sides of each standard, of a supporting-base adapted to hold the standards upright and about parallel to each other, a proper distance intervening between their adjacent edges, substantially as set forth.

4. In a device for turning garments, the combination, with two upright standards, two rings on their top ends, and a bracket-plate, of a supporting-table, substantially as set forth.

5. In a device for turning garments, the combination, with a table and a bracket-plate, of two upright standards slotted longitudinally a part of their length, set screws to adjust the standards to the bracket-plate, and a ring for each standard, that each projects nearly horizontal from like sides of the standards, substantially as set forth.

In testimony whereof I have signed this specification in the presence of two subscribing witnesses.

SAMUEL L. OTIS.
